NEW YORK.

COLLAR.

Application filed November 13, 1925. Serial No. 68,763.

Our present invention relates primarily to collars, and has particular reference to soft collars of the turn-down type, and to a method of making the same.

So-called soft collars of the usual construction have numerous well-known disadvantages, among which is the tendency to crease and wrinkle and to lose shape in a manner impairing the appearance of the collar and shortening its life.

It is among the objects of the present invention to provide a collar which will have none of the disadvantages heretofore inherent in collars of this type, and which is constructed in accordance with a method requiring the least amount of skill, material, and time.

More particularly, it is an object of this invention to provide a collar which will embody reinforcing means of such a character and so arranged as to render the manufacture simple and inexpensive and to produce a finished article having enhanced utility and appearance.

According to one feature of the invention, the collar is constituted of a neck band portion and a turn-down portion, and reinforcing strips are provided along the periphery of the turn-down portion in accordance with a predetermined plan. A feature of the invention lies in employing reinforcing strips which are relatively less yieldable in one direction than in a perpendicular direction, and in a preferred embodiment, we utilize hair cloth for this purpose, the strips being arranged in accordance with a predetermined plan with the hair threads disposed either longitudinally or transversely of the strip.

One of the important features of the invention lies in providing the end edges and the free longitudinal edge of the turn-down portion with hair cloth strips whose hair threads run longitudinally of the strips, i. e., substantially parallel to the edges; and in providing the remaining or inner longitudinal edge of the turn-down portion with a strip whose hair threads are arranged transversely. By virtue of this construction, the collar is made readily flexible and bendable at the portion which embraces the neck of a wearer so that the collar can conform smoothly to the required contour, while simultaneously the outer edges of the

turn-down portion are given a relative stiffness and reinforcement which causes the collar to lie smoothly and unwrinkled in its worn position. A further simultaneous advantageous result is produced by this construction in that the inner reinforcing strip defines the fold line and insures the repeated ready hinging of the turn-down portion along the same predetermined fold line.

In a preferred construction, the neck band portion is constituted of two superposed plies or components, an inner component and an outer component, and the turn-down portion is gripped and engaged by the neck band portion along its inner longitudinal edge. More particularly, in superposing the two plies referred to, we engage the reinforcing strip of the inner longitudinal edge of the turn-down portion between the plies in a manner concealing said edge entirely; and we thereupon stitch about the periphery of the neck band portion so that the superposed plies are united and the turn-down portion is engaged by the stitching along a line closely adjacent to the reinforcing strip.

For the attainment of the foregoing objects and such other objects as may hereinafter appear or be pointed out, we have illustrated one embodiment of our invention in the accompanying drawings, in which

Fig. 1 is a substantially plan view of the completed collar, portions thereof being broken away to show the interior construction;

Fig. 2 is a fragmentary view of the turn-down portion, showing a step in its method of manufacture;

Fig. 3 is a similar fragmentary view, showing the turn-down portion in position with respect to the neck band portion, just prior to attachment thereto; and

Fig. 4 is an exaggerated cross-sectional view taken along the line 4-4 of Fig. 1, showing in dotted lines the position assumed by the turn-down portion when the collar is ready for use.

Referring now to the drawings, it will be seen that we have provided a neck band portion 10 provided with suitable button holes 11 in a well-known manner, and a turn-down portion 12. Having a free or outer longitudinal edge 13, two end edges 14, preferably at a suitable angle to the edge 13 in accord-

ance with the contour of collar desired, and an inner longitudinal edge 15 substantially parallel to the edge 13.

In accordance with our invention, the 5 turn-down portion 12 is constructed preferably of a single ply of material, and the end edges and the free longitudinal edge are suitably seamed by twice turning them back upon themselves in a well-known manner.

10 Prior to the seaming operation, reinforcing strips are attached to these edges, as by stitching; so that after the seams are complete, the reinforcing strips will lie totally within the seams. The reinforcing strips 15 are constituted of strips of hair cloth whose longitudinal edges have been doubled back to overlie one side of the original strip, the latter being then doubled on itself to completely enclose these edges. This method of 20 forming the reinforcing strips is clearly shown in Fig. 4, and constitutes no essential feature of my invention, this method of enclosing the raw edges of a strip being well-known in the art. Referring more particularly to Fig. 4, the disposition of the reinforcing strip in the outer longitudinal edge 13 will be clear. The reinforcing strip 16, constituting in its final form four plies, is prevented from unfolding by a row of 25 stitching 17; it is then attached to the very edge of the portion 12 by a single row of stitching 18, and the edge is then folded on itself twice to form a seam completely enclosing the reinforcing 16. Two rows of 30 stitching 19 are then run along and through the seam to hold the latter in position.

This method of construction refers to the edges 13 and 14. The inner edge 15 of the turn-down portion 12 is not seamed, and a strip of reinforcing material 20 is attached thereto by two rows of stitching 21. The strip 20 comprises a strip substantially similar to the strips 16, its method of construction being clearly shown in Fig. 2, including 45 the line of stitching 22 originally run through the four plies of the strip to hold them together. The strip 20 is preferably attached to the edge 15 on the side of the material 12 opposite to the side upon which 50 the strips 16 have been attached.

In accordance with our invention, the strips 16 are arranged to have their hair threads substantially parallel to the edges upon which they are attached, whereas the 55 strip 20 is constructed to have its hair threads running transversely thereof so that they are not parallel, but substantially perpendicular, to the edge 15.

The turn-down portion 12 is now ready 60 for assembly with the neck band portion 10. The latter comprises two components, an inner component 23 and an outer component 24, each of which has its longitudinal edges doubled back to form seams; the portions 23 and 24 being then superposed to enclose the

doubled back edges therebetween. A line of stitching 25 is run peripherally about the neck band portion 10 to hold the portions 23 and 24 in superposed positions, but prior to this stitching operation, the turn-down 70 portion 12 is inserted between the plies 23 and 24, in a manner clearly shown in Figs. 3 and 4, so that the edge 15 and its reinforcing strip 20 are gripped and engaged between the plies 23 and 24. The line of 75 stitching 25 is then made, and it will be obvious that it will pass through the portion 12 along a line closely adjacent to the strip 20, thereby totally concealing the strip 20 and firmly attaching the turn-down portion 80 12 to the neck band portion 10.

It will be obvious that the strip 20 defines the fold line about which the portion 12 will hinge; and the arrangement of its hair threads perpendicularly to the edge 15 imparts to the strip 20 a relatively greater yieldability to bending in the direction the finished collar will be bent about the neck of a wearer. This permits the collar to conform smoothly to the particular contour of the neck, at the same time imparting to the upper edge of the neck band portion a certain body and rigidity which is extremely advantageous. On the other hand, the arrangement of the hair threads in the strips 95 16 imparts to these strips relatively greater resistance to bending longitudinally of the edges, and as a result these edges will retain their normal positions in a surprisingly efficient manner, effectually preventing wrinkling and creasing of the turn-down portion 100 when the collar is in use.

In some cases we prefer to stop the strips 16 along the end edges 14 at the fold line, instead of extending them completely to the 105 edge 15. This construction permits the collar to fold more easily along a fold line which has already been defined according to predetermined design by the strip 20.

It will be obvious that various changes in 110 the details herein described and illustrated for the purpose of explaining the nature of our invention, may be made by those skilled in the art without departing from the spirit and scope of my invention as expressed in 115 the appended claims. It is therefore intended that these details be interpreted as illustrative and not in a limiting sense.

Having thus disclosed our invention, and 120 illustrated its use, what we desire to secure by Letters Patent is:

1. In a turn-down soft collar of the character described, the combination of a neck band portion, a turn-down portion, and hair cloth reinforcing strips carried by the latter 125 along its periphery, the strips along the outer longitudinal edge and along the end edges being arranged with their hair threads substantially parallel to the respective edges.

2. In a turn-down soft collar of the char- 130

acter described, the combination of a neck band portion, a turn-down portion, and hair cloth reinforcing strips carried by the latter along its periphery, the strips along the outer longitudinal edge and along the end edges being arranged with their hair threads substantially parallel to the respective edges, and the strip along the inner longitudinal edge having its hair threads perpendicular to said edge.

3. In a turn-down soft collar of the character described, the combination of a neck band portion having superposed components, a turn-down portion having one longitudinal edge interposed between said components, and reinforcing strips carried by the turn-down portion along its periphery, the strip along the interposed edge being relatively more yieldable to longitudinal bending than to transverse bending.

4. In a turn-down soft collar of the character described, the combination of a neck band portion having superposed components, a turn-down portion having one longitudinal edge interposed between said components, and reinforcing strips carried by the turn-

down portion along its periphery, the strip along the interposed edge being relatively more yieldable to longitudinal bending than to transverse bending, and the strip along the free longitudinal edge being relatively more yieldable to transverse bending than to longitudinal bending.

5. In a turn-down soft collar of the character described, the combination of a neck band portion having superposed components, a turn-down portion having one longitudinal edge interposed between said components, and hair cloth reinforcing strips carried by the turn-down portion along its periphery, the strip along the interposed edge having its hair threads arranged transversely of said edge, whereby said strip will define the fold line and will simultaneously permit the collar to conform smoothly to the neck of a wearer.

In witness whereof, we have hereunto signed our names, this 2nd day of November, 1925.

MAX PUGATSKY.
BARNETT H. GOLDSTEIN.
